UNITED STATES PATENT OFFICE.

FRANK ERNEST MOSLEY, OF SHETTLESTON, GLASGOW, SCOTLAND.

APPARATUS FOR RECORDING THE DURATION OF SOUNDS AND INTERVALS OF SILENCE.

1,405,060.

Specification of Letters Patent. Patented Jan. 31, 1922.

Application filed November 29, 1920. Serial No. 427,133.

To all whom it may concern:

Be it known that I, FRANK ERNEST Mosley, a subject of the King of the United Kingdom of Great Britain and Ireland, and residing at Shettleston, Glasgow, Scotland, have invented a certain new and useful Improvement in Apparatus for Recording the Duration of Sounds and Intervals of Silence, of which the following is a specification.

This invention relates to apparatus adapted to record the durations of sounds or successions of sounds and intervals of silence for the description of moving pictures or the durations of sounds or successions of sounds (in the form of song, speech or otherwise) intended to accompany actions or gestures of characters or incidents depicted in moving pictures and intervals of silence between such sounds or successions of sounds.

The production of a graph representative of durations of sounds or successions of sounds and intervals of silence is a preliminary to the production of a selector-commutator employed for controlling the operation of a phonograph or phonographs to be operated in conjunction with a cinematographic machine for the production of talking pictures, singing pictures and the like as described in the specification of the co-pending applications Nos. 427,134 and 427,135 filed simultaneously herewith.

Apparatus according to the invention comprises a carrier for a medium to be marked and a marking device, of which one travels past the other at a speed bearing a given relation to the speed of a moving part of the cinematographic machine. Preferably the marking device is normally stationary in relation to the carrier which latter comprises a drum or the like positively driven through the intermediary of reduction gearing from a rotating part of a cinematographic machine, such as, for example, the film-feeding spindle, the speed reduction being preferably such that the drum makes no more than a single rotation in the time required to feed the film through the cinematographic machine.

The marking device may comprise any number of pencils or the like individually movable into and out of engagement with

the graph-receiving medium carried by the drum, under the control of an operator who may, for example, manipulate keys the actuation of each of which establishes contact between a corresponding pencil or the like and the graph-receiving medium, the time during which each key is depressed, for example, being represented graphically by a mark produced on the medium by the corresponding pencil and the time during which each key is released being represented by a blank on the medium, so that if each key be assigned to a given character in the photoplay or the like and be depressed during such time as the character in question is assumed to be vocal, the completed graph will furnish a record of the times when each character was assumed to be vocal and when he or she was assumed to be silent between speeches or the like, the representations of periods of sounds or successions of sounds being positioned and dimensioned in accurate correspondence with the times when sounds are to be heard in the display of the picture.

I shall now proceed to describe in detail by way of example a construction of apparatus embodying the invention and in this connection refer to the accompanying drawings in which Fig. 1 is a plan and Fig. 2 an elevation with the drum removed to show the pencils in elevation. Fig. 3 is an end view. Fig. 4 is a detail view.

Referring to the drawings, 1 denotes a rotatable drum serving to carry a suitably ruled graph paper 2, said drum being removably secured in a predetermined position to a mandrel on a shaft 3 which in practice is connected through reduction gearing with the film-feeding spindle of a cinematographic machine. In the construction illustrated an extension of the shaft 3 carries a worm wheel 4 meshing with a worm 5 on a short shaft 6 carrying also a bevel gear 7 meshing with a bevel gear 8 on one end of a shaft 9 at the opposite end of which is a bevel gear 10 engaged by a bevel gear 11 on a spindle 12 carrying a bevel gear 13 meshing with a bevel gear 14 on a shaft 15 operatively connected by any suitable means with the film-feeding spindle of a cinematograph projector (not shown).

Provision is made for disconnecting the drum from the driving gear and for arresting rotation of the drum.

- As shown in Fig. 4, the shaft 6 on which the worm 5 is cut or fixed is adapted to be lowered, the lowering of the shaft 6 bringing the worm 5 out of mesh with the worm wheel 4. To lower the shaft 6, the operator depresses the lever 16 attached to 10 detents 17 on which rests the bearing 18 supporting one end of the shaft 6, thereby allowing the shaft 6 to swing around the axis of the shaft 9 carried by bearing members 19 integral with the main bearing 20 of the shaft 6. To bring the worm 5 again into mesh, the free end of the shaft 6 is lifted, whereupon the spring 21 restores the detents 17 to supporting position. Connected to the worm wheel 4 is a ring 22 formed with a peripheral notch 23 engageable by a spring-pressed pin 24 when the drum is in correct position for starting the production of a graph. As the drum may have performed only a partial rotation by 25 the time the film has completely passed through the cinematographic machine, it is desirable to be able to bring the drum readily to the same starting position independently of the cinematographic machine. 30 With the present arrangement, when the worm 5 is out of mesh with the worm wheel 4, and the spring-pressed pin 24 is disengaged from the notch 23, the drum 1 and shaft 3 may be further rotated by manual 35 operation of a knob 25 on the end of the shaft 3 until the notch 23 is in position to be engaged by the pin 24. There is but one possible angular position of the drum 1 relatively to the shaft 3, the drum being 40 secured in driving position by means of the boss 26 fixed on the driving flange 27 and by the nut 28 threaded on a boss 29 of the drum-carrying mandrel 30 and pressing on the washer 31. 45 I have not considered it necessary to describe in further detail the construction and arrangement of the speed-reducing gear illustrated, as any known or suitable speed reducing gear may be employed for transmitting rotary motion of the film-feeding spindle to the drum 1 at the required speed reduction.
- Arranged in juxtaposition to the drum is a marking device comprising a frame in 50 which is mounted a series of pencils 32 spaced apart axially of the drum and each pointing towards the drum, the tip of each pencil being normally held retracted from the drum by a spring 33 interposed between 55 a fixed stop 34 and a collar 35 on a cradle 36 to which the pencil is clamped by means of a thumb screw 37. A cord 38 connected at one end to the cradle 36 is led around guide pulleys 39 and 40 and connected at 60 the opposite end to an armature 41 adapted

to be attracted on the excitation of an electro-magnet 42 whereby the cord is tensioned to urge the pencil point against the paper on the drum, the spring 33 acting on de-energization of the electro-magnet 42 to restore the pencil 32 to initial position clear of the paper.

To avoid harsh pressure on the paper by the pencil, a spring 43 is inserted between the cradle 36 and the end of the cord 38 adjacent thereto.

As will be seen from the diagrammatic representation of the electrical connections in Fig. 1, current from a source 44 passes by way of leads 45, 45', 45² etc., across a 80 keyboard with keys 46, 46', 46² etc., to terminals 47, 47', 47², etc., connected to the windings of the respective electro-magnets 42 whence connections 48, 48', 48², etc., are led to a bus-bar 49 from which a return connection 50 is led to the battery 44.

The leads 45, 45', 45², etc., are each interrupted at the keyboard so that the exciting circuit of each electro-magnet is normally open. Depression of a key effects, 90 however, closure of the circuit of the corresponding electro-magnet which remains excited so long only as the key is depressed.

It will be appreciated from the foregoing that an operator or operators following the representation of a picture can readily manipulate the keys so that as each character is vocal the point of the pencil assigned to that character will be in contact with the paper, but that when any character is silent 100 between speeches or the like the corresponding pencil will be out of contact with the paper, it being understood that in practice time margins anterior and subsequent to the actual production of sound may be allowed 105 for.

In the embodiment illustrated ten pencils and actuating devices therefor are illustrated, it being evident, however, that the number of pencils employed will be determined by circumstances. In given cases a single pencil will suffice.

By the term "sound" is intended to be included all varieties of sounds capable of reproduction by a talking machine, i. e., 110 not only vocal sounds but also naturally or artificially produced phenomena capable of perception by the auditory organs.

I claim:—

Apparatus for recording the duration of 120 sounds and intervals of silence corresponding to the periods of activity and inactivity of a talking machine to be operated in conjunction with a cinematographic machine, comprising the combination of a carrying 125 device for the medium to be marked, a marking device, and key means operable by an observer for actuating said marking device, one of said devices being operatively connected to the cinematographic machine 130

to travel relatively to the other device at a speed proportionate to the speed of a moving part of the cinematographic machine, and the other device being adapted to be
5 rendered effective and ineffective at times correlated to the periods of activity and inactivity of the talking machine.

In testimony whereof I have signed my name to this specification in the presence of two subscribing witnesses.

FRANK ERNEST MOSLEY.
